INTERCHANGEABLE HANDBAG

Irving Peyser, Brooklyn, N. Y.

Application December 6, 1949, Serial No. 131,390

2 Claims. (Cl. 150—28)

1

This invention relates to new and useful improvements in ladies' handbags of the kind incorporating a plurality of complementary portions one of which is interchangeable with another or with any one of several others, to provide different color combinations and other effects, as for from time to time adapting a selected color or dominating color to be well matched with a costume then worn; and, more particularly, the aim is to provide a novel and valuable such handbag characterized by a construction such that of said complementary portions one is a lower body portion, this providing also the bottom wall of the handbag, and the other is an upper detachable body portion arranged for ready dependable attachment near its bottom to the lower body portion near its top, said upper body portion carrying the entirety of the bag closure and handle means.

Preferably, the means last-named is a single means for acting as a readily openable closure for the upper body portion and also for acting as the handbag handle.

A feature of the invention, further, is that said means last-named is of such nature that an upper body portion, after being detached from said lower body portion, may be turned inside out, and then, with said means still operative for the purposes stated, said upper body portion may be again attached to said lower body portion; thereby, with the lining of said upper body portion of a contrasting color to the material used for the outer side thereof, to change the color or otherwise modify the appearance of the component of the complete handbag contributed by said upper body portion.

According to this arrangement, and with, whenever desired, a plurality of upper body portions being furnished with a single lower body portion, and further with, for example, all said upper body portions having a contrasting lining as above, the number of possible variations of the appearance of the bag as a whole would equal the number of said upper body portions multiplied by two.

In regard to the various attractive yet different handbag ensembles which may be provided by the invention, these differences may reside in contrasting colorations, as already mentioned, or they may result from different surface-formation characteristics, as, for instance, those respectively typical of the weave of a textile fabric, or of the grain of a leather or of the nature and mode of application of an enamel coating, etc.

As the invention is also desirably carried out, the lower body portion is of relatively stiff and rigid kind, as by being made of plastic, wood, metal or other suitable material, and an upper body portion is made of relatively limp or at least fairly

2

freely flexible material, such as a textile fabric, a leather or the like.

Said upper and lower body portions below will respectively be called the upper and lower body members.

For further comprehension of the invention, and of the objects and advantages thereof, reference will be had to the following description and accompanying drawings, and to the appended 10 claims in which the various novel features of the invention are more particularly set forth.

In the accompanying drawings forming a material part of this disclosure:

Fig. 1 is a perspective view showing a now approved embodiment of the invention, with the handbag fully established by inclusion of a pair of interconnected upper and lower body members.

Fig. 2 is a bottom plan view of the upper body member.

Fig. 3 is a top plan view of the lower body member.

Fig. 4 is an enlarged central vertical section taken on the line 4—4 of Fig. 1.

The handbag, according to the present invention, includes a lower body member 10 in the form of a cylindrical cup made of a suitable plastic and incorporating a side wall 11 and a circular bottom wall 12. Said wall 11 is also shown as of uniform height all around the member 10. As 25 is to be understood, however, the wall 11 may be undulant at its top or otherwise modified as to its height at various points around the member 10; and, also, said member 10 may be otherwise than cylindrical, as by being oval, elliptical, half-round, 30 oblongovate, square or otherwise polygonal in horizontal section, which section, further, may vary at different levels, as, for instance, to have the said member 10 taper upward, taper downward or be of maximum cross-sectional expanse 35 intermediate its top and bottom.

The upper body member 14 is of tubular form. In the present case, since the top edge of the wall 11 of the lower body member 10 is shown as lying in a single plane, the bottom portion of said member 14 is such that the bottom edge of said member 14 may also lie in a single plane when the bottom of the member 14 is distended for curvilinear extension in conformity with the curvature of the wall 11. The bottom of the member 14 is also 45 so dimensioned that the diameter of the circle corresponding to said curvilinear extension is substantially the same as the outer diameter of the wall 11. Then the bottom marginal portion of the member 14 may be telescoped snugly over the 50 upper marginal portion of the wall 11 as shown in Fig. 4.

The upper body member 14 is of two-ply construction all over; these plies, 15 and 16, being of

flexible materials of different coloration or other surface appearances as already mentioned. The elements 15 and 16 may be pieces cut from said materials when flat, and then formed into tubular units, as by employing a suitable seam not shown in regard to each and extending from top to bottom thereof. In joining tubular units thus made from the two pieces 15 and 16, as immediately below explained, the edge portions of said pieces projecting beyond the threads participating in said seams will be pocketed between the two units.

With said units arranged one within the other, all around the bottoms thereof the constituent pieces 15 and 16 thereof are marginally inturned, as shown respectively at 17 and 18 in Fig. 4, and said units are there seamed together as by a stitching 19, to give a good finish to the bottom of the body member 14 all around the same.

The edge portions of said tubular units at the tops thereof are similarly marginally inturned, as also shown in Fig. 4, and then a stitching 20 is applied to establish a seam giving a good finish to the top of the body member 14 all around the same. The upper portion of said member 14 is indented at two opposite points around said member, to provide two like flaps 21 and 22, and the seam last referred to follows such indentations as will be noted in Figs. 1 and 4.

Girthwise of the body member 14, two lines 23 and 24 of stitching are applied, there to lock together the two pieces 15 and 16. The stitching 23 is shown as just below the flaps 21 and 22, and the stitching 24 is enough lower down on the member 14 to provide a tunnel 25 running all around said member and of a width to accomodate a ribbon, tape, leather-strip or other selected type of draw-string 26. Said tunnel, as at the point 27 in Figs. 1 and 2, is interrupted by a preferably vertically elongate suitably finished off opening through both the pieces 15 and 16.

The openings at the point 27 are for having extended therethrough the two end portions 26^a and 26^b of the draw-string 26. The width of the tunnel 25, that is, the spacing between the stitches 23 and 24, is made sufficiently large beyond the draw-string end portions 26^a and 26^b to permit the middle portion of the draw-string to be extended along the tunnel fully encircling thereof, for most efficient operation of the draw-string in tightly closing the handbag top by pulling on both the draw-string end portions 26^a and 26^b. Such encircling of the middle portion of the draw-string is clearly indicated by the reference numerals 26^a and 26^b as they appear in Fig. 4.

In carrying the handbag, the said draw-string end portions 26^a and 26^b serve as a suspending handle.

For detachably securing the upper body member 14 to the lower body member 10, a means is provided which includes a plurality of button-like headed studs 28, preferably evenly spaced around the periphery of said member 10 and fixedly carried by and radially offset from the said member 10 near the top thereof. As herein shown, six of these studs 28, all alike, are present. Said means further includes a corresponding number of evenly spaced loops 29 of flexible material dependent from the bottom of the body member 14. The upper ends of the strip-like elements from which said loops are desirably made are nested inside the finishing seam at the bottom of said member 14 and there anchored in place by the stitching 19.

As the handbag assembly is shown in the drawing, the piece 15 of the body member 14 is at the

outside, with the piece 16 acting as a lining. At any time desired, and after temporary detachment of the loops 29 from the studs 28, the said member 14 may be readily turned inside out, thereby to place the piece 16 at the outside and locate the piece 15 as a lining, but nevertheless the draw-string 26 is operable as before.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent, is:

1. Connecting means for a handbag having a rigid lower body member and a flexible reversible upper body member which can be turned to have either side faced outward, comprising equally spaced fastener members mounted on the outside of the lower body member and in a line encircling the lower body member closely adjacent its top, the bottom portion of the upper body member being of an inside diameter to be snugly telescoped over the top of the lower body member above said fastener members regardless of which of its sides is faced outward, and complementary fastener members depending from the bottom edge of the upper body member to be exposed for engagement with said first-mentioned fastener members regardless of which of the sides of the upper body member is faced outward.

2. Connecting means for a handbag having a rigid lower body member and a flexible reversible upper body member which can be turned to have either side faced outward, comprising equally spaced fastener members mounted on the outside

30 of the lower body member and in a line encircling the lower body member closely adjacent its top, the bottom portion of the upper body member being of an inside diameter to be snugly telescoped over the top of the lower body member above said fastener members regardless of which of its sides is faced outward, and complementary

35 fastener members depending from the bottom edge of the upper body member to be exposed for engagement with said first-mentioned fastener members regardless of which of the sides of the upper body member is faced outward.

2. Connecting means for a handbag having a rigid lower body member and a flexible reversible upper body member which can be turned to have either side faced outward, comprising equally spaced fastener members mounted on the outside

40 of the lower body member and in a line encircling the lower body member closely adjacent its top, the bottom portion of the upper body member being of an inside diameter to be snugly telescoped over the top of the lower body member above said fastener members regardless of which of its sides is faced outward, and complementary

45 fastener members depending from the bottom edge of the upper body member to be exposed for engagement with said first-mentioned fastener members regardless of which of the sides of the upper body member is faced outward, said first-mentioned fastener members comprising headed

50 studs extending radially outward from the lower body member, said complementary fastener members comprising loops depending from the bottom edge of the upper body member and engageable with said headed studs.

IRVING PEYSER.
